UNITED STATES PATENT OFFICE.

FRANK J. KARNIK AND AUGUST F. KUBESH, OF VESELEYVILLE, NORTH DAKOTA.

FLAX COMBING AND CLEANING MACHINE.

SPECIFICATION forming part of Letters Patent No. 782,140, dated February 7, 1905.

Application filed August 17, 1904. Serial No. 221,147.

To all whom it may concern:

Be it known that we, FRANK J. KARNIK and AUGUST F. KUBESH, citizens of the United States, residing at Veseleyville, in the county of Walsh, State of North Dakota, have invented certain new and useful Improvements in Flax Combing and Cleaning Machines; and we do hereby declare the following to be a full, clear, and exact description of the invention, such as will enable others skilled in the art to which it appertains to make and use the same.

This invention relates to machines for combing and cleaning flax; and it has for its object to provide an apparatus in the use of which the fibers will be thoroughly combed and will be cleaned without breaking or otherwise injuring them, a further object of the invention being to provide a construction in which the desired results will be accomplished with the expenditure of little time and energy.

Other objects and advantages of the invention will be understood from the following description.

In the drawings forming a portion of this specification, in which like numerals of reference indicate similar parts in the several views, Figure 1 is a top plan view showing a machine embodying the present invention. Fig. 2 is a side elevation of the machine. Fig. 3 is a vertical longitudinal section of the machine. Fig. 4 is a vertical section taken transversely through the machine in the plane of the pickers, one of the pickers being in elevation.

Referring now to the drawings, there is shown a machine comprising a base-frame 10, upon which are uprights 11, that support the parallel horizontal beams 12 and 13, forming the sides of the body of the machine. The inner lower corners of the beams 12 and 13 are grooved or rabbeted, and in these rabbets are disposed the end portions of the transverse hackle-bars 14, which are bolted or otherwise secured to the beams in any suitable manner. The bars serve to strengthen the body of the machine and give thereto the necessary rigidity.

Upon the beams 12 and 13, respectively, and adjacent to each end thereof are mount-

ed journal-boxes 15 and 16, and in each pair of journal-boxes are mounted the outwardly-turned ends of a double crank-shaft, the shaft in the boxes at one end of the machine being shown at 17, while the shaft at the opposite or discharge end of the machine is shown at 19. One crank of each shaft is between the bearings in which the shaft is mounted, while the other crank is at the outer side of the bearing 16, and these last-named cranks (indicated at 20) are connected by a pitman 21. Those cranks of the shafts that are between the journal-boxes 15 and 16 (shown at 22 and 23) engage the journal-boxes 24 and 25, respectively, upon the opposite ends of the sides 26 and 27 of a movable hackle-frame. The sides 26 and 27 are connected by the hackle-bars 28, the endmost bar at the inner end of the hackle being secured against the beveled end faces 29 of the sides 26 and 27, and through this endmost bar and at an inclination so as to project at right angles to the beveled faces are inserted hackle-teeth 30, which project from the lower face of the bar and are tapered in the direction of their free ends. The free end portions of the teeth 30 are bent so that they project only slightly rearwardly. Through the remaining bars 28 are inserted hackle-teeth 31, which project from the lower faces of the bars and are tapered toward their lower ends and project slightly rearwardly of the machine. Extending upwardly through the lower hackle-bars 14 are hackle-teeth 32, which project from the upper faces of the bars and slightly in the direction of the intake end of the machine, all of the hackle-teeth being riveted or otherwise secured to the bars. The crank-shaft at the discharge end of the machine is provided with a belt-wheel 33 for rotating the shaft to give to the movable hackle-frame a rotary movement, the frame when in proximity to the fixed frame moving toward the discharge end of the latter for a purpose to be presently explained.

Upon the beams 12 and 13 and spaced slightly from the journal-boxes 15 and 16 at the inner end of the machine are journal-boxes 35, in which is journaled a picker-shaft

36, which carries a picker. The picker comprises end disks 37, which are fixed to the shaft 36 between and adjacent to the boxes 35 and which disks are connected by metal plates 38. Each of the plates has end wings 39 and 40, which are secured flat against the inner faces of the disks 37, one longitudinal edge portion of each plate having triangular teeth 41, which project beyond the peripheries 5 of the disks and are bent slightly in a direction opposite to that of rotation of the picker. The plates are displaced slightly from positions 10 radially of the disks to such a degree that if continued they would pass at one side of the 15 picker-shaft. At the under sides of the beams 12 and 13 are other journal-boxes 42, in which is journaled a transverse picker-shaft 43, carrying a picker, including end disks 44, against the inner faces of which are 20 secured the laterally-turned wings 47 of plates 48, that extend longitudinally of the picker and which at one longitudinal edge have the 25 triangular teeth 49, which project beyond the peripheries of the disks and are bent slightly 30 in the direction opposite to that of rotation of the picker. It will be noted that the upper picker is of greater diameter than the lower picker, while the number of toothed plates or 35 combs is the same in both pickers. The upper picker-shaft is provided with a gear-wheel 50, which engages a pinion 51 on the lower picker-shaft, these engaging members being so proportioned as to permit of five 40 hundred revolutions of the lower picker to 35 three hundred revolutions of the upper picker, the pickers being driven from a belt-wheel 53, fixed to one end of the upper picker-shaft, the opposite end of the upper picker-shaft having a belt-wheel 54, with which is engaged 45 a belt 55, which engages also with the belt-wheel 33.

The flax to be treated is fed into a hopper 57, which carries it into position between the pickers, which are rotated with their mutually-adjacent faces in the direction of the 45 hackle, and by reason of the fact that the lower picker rotates at a higher speed than the upper picker and that the teeth are deflected oppositely to the directions of rotation of the pickers the flax is held upon the upper teeth, while the lower teeth serve to comb it. To insure disengagement of the flax from the upper teeth, a doffer is provided and consists of a transverse bar 58, which is carried by the curved end supports 59 and 60, which are hinged to the beams 12 and 13, so that the doffer may be swung toward and away from the upper picker. The 55 free ends of the curved end supports, which 60 latter pass part way around the upper picker-shaft, rest upon the rear end portions of the beams 12 and 13. The rear end portions of the curved end pieces or end supports are connected by a transverse brace 61, and this

brace, in connection with the doffer-plate and 65 end supports, forms a frame for a semicylindrical housing 62, which extends over and part way around the upper picker. A semi-cylindrical housing 64 is provided for the 70 under side of the lower picker.

To receive the flax from the pickers and carry it to the hackle, a feed-roller 69 is provided having trunnions mounted in bearings in the beams 12 and 13, the roller being located between the lower picker and the lower 75 hackle-bars and projecting slightly above the latter and having radiating pins or teeth 70. The feed-roller is driven with its upper side in the direction of the hackle by means of a belt engaged with pulleys 72 and 73 on the 80 lower picker-shaft and a trunnion of the roller. The feed-roller extends slightly beneath the inner end bar of the movable hackle-frame, and in the movement of said frame the teeth of this bar move entirely over the roller, so 85 as to engage the flax thereon and carry it onto the lower or fixed hackle-bars. The movement of the upper hackle-frame causes its teeth to engage the flax on the lower frame and carry it rearwardly of the latter and discharge it finally from its rear end, the teeth of the two frames being positioned so that the upper teeth enter between the lower teeth and serve to remove waste matter and further straighten the fibers and separate them without breaking them.

What is claimed is—

1. In a machine of the class described, the combination with pickers, of a hackle comprising a fixed member and a movable feeding member and a feeding-roller disposed between the pickers and the hackle and adapted to carry materials from the former to the latter, the feeding member of the hackle being movable over the roller to engage and carry 100 material therefrom to the fixed member of the 105 hackle.

2. In a machine of the class described, the combination with pickers, of a hackle comprising relatively fixed and movable frames 110 having teeth projecting toward each other, means for moving one of the frames longitudinally of the other frame and means for feeding the material to be treated, from the pickers to the hackle.

3. A machine of the class described comprising a hackle comprising a fixed member including spaced bars having upwardly-projecting teeth and a second member having downwardly-projecting teeth and mounted 120 for rotary movement longitudinally of the fixed member and pickers disposed for treatment of material in its passage to the hackle.

4. A machine of the class described comprising a hackle embracing a fixed member including spaced bars having upwardly-projecting teeth and a second member having downwardly-projecting teeth and mounted 125

for rotary movement longitudinally of the fixed member, pickers disposed for treatment of material in its passage to the hackle, and means for carrying the material from the pickers to the hackle and in coöperation with which the movable member of the hackle is operable to remove the material therefrom.

In testimony whereof we affix our signatures in presence of two witnesses.

FR. J. KARNIK.

AUGUST F. KUBESH.
